Primary Examiner — Cathron Brooks*Assistant Examiner* — Daniel J Domino(74) *Attorney, Agent, or Firm* — QuickPatents; Kevin Prince(57) **CLAIM**

I claim the ornamental design for an L-type pipe fitting, as shown and described.

DESCRIPTION

FIG. 1 is a perspective view of an L-type pipe fitting, showing my new design;

FIG. 2 is a front elevational view thereof, the right-side elevational view being a mirror image thereof;

FIG. 3 is a left-side elevational view thereof, the rear elevational view being a mirror image thereof; and,

FIG. 4 is a top plan view thereof, the bottom plan view being a mirror image thereof.
